Primary Examiner — Barbara Fox*Assistant Examiner* — Kristin E Reed(74) *Attorney, Agent, or Firm* — Cantor Colburn LLP(57) **CLAIM**

The ornamental design for a wearable electronic device, as shown and described.

DESCRIPTION

FIG. 1 is a top perspective view of a wearable electronic device showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof;

FIG. 9 is a bottom perspective view thereof; and,

FIG. 10 is a top perspective view of a wearable electronic device with an additional display device as shown in a state of use.

The broken lines in the figures show portions of the wearable electronic device which form no part of the claimed design. The dot-dash-dot lines in FIG. 10 showing the additional display device form no part of the claimed design.

1 Claim, 10 Drawing Sheets(58) **Field of Classification Search**
